Primary Examiner — Susan Bennett Hattan*Assistant Examiner* — Brett Miller(74) *Attorney, Agent, or Firm* — HP Inc. Patent Department(57) **CLAIM**

We claim the ornamental design for an additive manufacturing device, as shown and described.

DESCRIPTION

FIG. 1 is a front perspective view of an additive manufacturing device;

FIG. 2 is a front left perspective view thereof;

FIG. 3 is a front right perspective view thereof;

FIG. 4 is a top view thereof;

FIG. 5 is a front view thereof;

FIG. 6 is a left side view thereof;

FIG. 7 is a rear view thereof; and,

FIG. 8 is a right side view thereof.

The broken lines in the drawings are for illustrative purposes only, shown to indicate environmental subject matter, and form no part of the claimed design.
